W. H. LYNCH

ROTARY SAND BAILER

Filed Feb. 8, 1926

INVENTOR
WILLIAM H. LYNCH.
BY
H. A. Dreckman
ATTORNEY

UNITED STATES PATENT OFFICE.

WILLIAM H. LYNCH, OF LOS ANGELES, CALIFORNIA.

ROTARY SAND BAILER.

Application filed February 8, 1926. Serial No. 86,946.

This invention relates to that type of bailer which is adapted to be inserted into a well and remove sand, dirt, and other extraneous matter therefrom, and is particularly applicable to oil wells.

The prime object of my invention is to provide a cutting tool, operable in conjunction with a bailer.

Another object is to provide means operable by the weight of the tool to actuate the cutting tool.

It has heretofore been necessary to first insert a drill into the well and break up the sand and gravel, then remove the drill, then 15 insert a bailer, to remove the sand, etc., thus consuming a great deal of time.

A further object of my invention is the saving of time, incident to the drilling of a well, and the provision of a bailing drill, 20 which is efficient in operation, and simple in construction.

Other objects, advantages and features of invention may appear from the accompanying drawing the subjoined detailed description, and the appended claims.

In the drawing in which the preferred form of my invention is illustrated—

Fig. 1 is a longitudinal sectional view of my bailer.

Fig. 2 is an enlarged fragmentary longitudinal sectional view of the upper part of the bailer.

Fig. 3 is an enlarged fragmentary longitudinal sectional view of the lower part of 35 the bailer.

Fig. 4 is a sectional view taken on line 4—4 of Fig. 1.

Fig. 5 is a sectional view taken on line 5—5 of Fig. 1.

Fig. 6 is a sectional view taken on line 6—6 of Fig. 1.

Fig. 7 is a sectional view taken on line 7—7 of Fig. 1.

Referring more particularly to the drawing my bailer consists of a substantially cylindrical head 1, to the lower end of which a casing 2 is a threaded or otherwise suitably secured. A thrust bar 3 is slidably journaled in the head 1, and is prevented from rotating by a pair of longitudinal tongues 4, projecting from the sides thereof, and slidable in suitable grooves 5, in the head 1. A bar 6 is secured to the upper end of the thrust bar 3, preferably by threading thereon, and is of sufficient weight to actuate the thrust bar, which will be further

described. A cable (not shown) is secured to the bar 6 and extends upwards to the actuating mechanism at the top of the well, whereby the bailer is operated. A foot 7 is 60 threaded to the bottom of the thrust bar 3 and is slidably journaled in the casing 2.

A nipple bushing 8 is threaded to the bottom of the casing 2, and a short length of tubing 9 connects this bushing and a second 65 nipple bushing 10, being threaded to both bushings. A lower casing 11 is threaded at its upper end to the bushing 10, and a saw tooth shoe 12 is threaded to the lower end thereof. 70

The drilling mechanism will now be described. An upper drill rod 13, has a threaded or twisted section 14 at the upper end thereof. The threaded section extends into the hollow thrust bar 3 and extends 75 through the foot 7 which is threaded to receive it. The lower end of the rod 13 is journaled in the bushing 8. A coupling or joint member 15 is secured to the lower end of the rod 13, which member is coupled to 80 the lower joint member 16. The member 16 has a hollow depending sleeve 17, which is journaled in the bushing 10. A lower drill rod 18 has a squared upper end 19, which fits into the square hole 20 in the member 16, 85 thus slidably coupling the said rod and member. A drilling bit 20' of usual construction is secured to the bottom of the rod 18. This rod is such a length that when the top is adjusted to the rod 13, the bit 20' 90 will be within the casing 11, that is above the lower edge thereof.

A valve seat 21 is integrally formed on the upper end of the shoe 12, and a valve 22 rests therein. The drill rod 18 extends 95 therethrough and a spacing collar 23, spaces the valve from the bit 20'. A brace and bearing spider 24 is formed in the casing 11, and is so positioned above the valve seat 21 that the valve will engage it and prevent the bit 20' from contacting with said valve seat 21. A spring 25 surrounds the rod 18 and bears against a washer resting against the bushing 10 and against a ring 26 on the rod and an adjustable collar 27 on the rod 19 engages 100 the spider 24 to limit the downward movement of said rod.

Fluid ports 28 are provided in the casing 11, and a sand dump 29 is provided, adjacent the spider 24.

In operation my bailer is lowered into the well, and the bit 20' falls downwardly in

advance of the shoe 12 under the urge of the spring 25. When sand is reached the rod 18 will partly support the bailer, and the thrust rod 3 and foot 7 will drop under the urge 5 of the heavy bar 6 traveling over the threads 14 on the rod 13 and causing said rod to rotate which also rotates the rod 18 and bit 20 thru the coupling 15 and 16. Repeated 10 raising and lowering of the bar 6, will continue to actuate the bit. The casings 2 and 11 will move downwardly as the bit advances and the sand will travel up past the valve 22 into the casing 11. If a particularly hard strata is reached the bit 20' and 15 18 will move upwardly against the spring 25, allowing the saw tooth shoe 12 to cut and preventing damage of the bit.

In oil wells the tool will operate in a liquid, and I have provided liquid relief 20 ports 30 and 31, adjacent the upper and lower limits of travel respectively, of the foot 7. After the foot passes a port in its travel a certain amount of fluid is trapped 25 which cushions the blow of said foot against the head 1 or bushing 8. Small bleed holes 32 are adjacent the bushing 10 and holes 33 extend thru the bar 6 from a recess 34 communicating with the hollow thrust bar 3. A fluid space 35 is provided between the casing 30 2 and thrust bar 3. The foot 7, does not accurately engage the threaded portion of the rod 13 to the exclusion of all water. Therefore, as this foot reciprocates, water 35 will be forced past the threads consequently the ports 33 are necessary.

I claim.

1. A sand bailer comprising a casing, a rod in said casing, means journaling said rod, threads on said rod, a foot adapted to 40 engage the threads on said rod, means slidably and non-rotatably mounting said foot and means to reciprocate said foot to rotate said rod, a valve seat adjacent the lower end of said casing, and a valve adapted to rest 45 on said seat and surrounding said rod, and teeth on the lower end of said casing whereby the casing is nonrotatably held while the rod is rotated.

2. A sand bailer comprising a casing, 50 upper and lower aligned rods in said casing, means slidably coupling said rods together, spring means urging said lower rod downwardly, means journaling said rods, means to rotate said rods, and valve means adjacent the lower end of said casing.

3. A sand bailer comprising a casing a 55 rod in said casing, means journaling said rod in the casing, threads on said rod, a cutter secured to the bottom of said rod, a thrust bar reciprocally and nonrotatably 60 mounted in said casing, a foot secured to said bar slidably engaging the threads of

said bar, a heavy bar secured to said thrust bar, means to reciprocate said heavy bar, and valve means adjacent the lower end of 65 said casing.

4. A sand bailer comprising a casing, a rod in said casing, means journaling said rod in the casing, threads on said rod, a cutter secured to the bottom of said rod, a thrust 70 bar reciprocally and non-rotatably mounted in the casing, a threaded foot secured to said bar, said threaded rod being adapted to extend through the foot and engaging the threads therein, means to reciprocate said 75 thrust bar to rotate said rod, a lower drill rod slidably mounted in said casing, means coupling said threaded rod and lower drill rod, and valve means adjacent the lower end of said casing.

5. A sand bailer comprising a casing, a rod in said casing, means journaling said rod in the casing, threads on said rod, a thrust bar reciprocally and non-rotatably 80 mounted in the casing, a threaded foot secured to said bar, said threaded rod being adapted to extend through the foot, means to reciprocate said thrust bar to rotate said rod, a lower drill rod slidably mounted in said casing, a cutter on said lower drill rod, 85 means coupling said threaded rod and lower drill rod, and valve means adjacent the lower end of said casing, and teeth on the lower end of said casing whereby the casing is nonrotatably held while the rod is rotated.

6. A sand bailer comprising a casing, a rod in said casing, means journaling said rod in the casing, threads on said rod, a cutter on said rod, a thrust bar reciprocally and 100 nonrotatably mounted in said casing, a foot secured to said bar slidably engaging said threaded bar, a heavy bar secured to said thrust bar, means to reciprocate said heavy bar, and valve means adjacent a lower end 105 of said casing, and teeth on the lower end of said casing whereby the casing is nonrotatably held while the rod is rotated.

7. A sand bailer comprising a casing, a rod in said casing, means journaling said 110 rod in the casing, threads on said rod, a thrust bar reciprocally and nonrotatably mounted in said casing, a foot secured to said bar slidably engaging the threads of said rod, a heavy bar secured to said thrust 115 bar, means to reciprocate said heavy bar, a lower drill rod slidably mounted in the casing, means coupling said drill rod and threaded rod, spring means urging said drill rod downwardly, and valve means adjacent 120 the lower end of said casing.

In witness whereof I have this day set my hand.

WILLIAM H. LYNCH.
